UNITED STATES PATENT OFFICE.

FRANK J. GRESSLY, OF NEW YORK, N. Y.

DESIGN FOR A BASE FOR MATCH-BOX HOLDERS.

SPECIFICATION forming part of Design No. 32,787, dated May 29, 1900.

Application filed May 4, 1900. Serial No. 15,546. Term of patent 7 years.

To all whom it may concern:

Be it known that I, FRANK J. GRESSLY, a citizen of the United States, residing at the city of New York, (Brooklyn,) county of Kings, 5 and State of New York, have invented and produced a new and original Design for Bases for Match-Box Holders, of which the following is a specification.

My invention relates to a new and original design for bases for match-box holders or similar articles; and it consists in the configuration and ornamentation, substantially as shown in the accompanying drawings, forming part of this specification, in which—

15 Figure 1 is a plan view; and Fig. 2 is a sectional view on the line $x-x$, Fig. 1.

The outline of the base 1 is generally square in plan, with a central circular depression 2 and conical projection 3. Diametrically opposed to each other and at the angles of the square and extending inwardly upon the ex-

terior of the base are the cherubic heads 4, surrounded by the curved bars 6. The exterior of the depression 2 is conical on top and has a shell-like ornamentation 7, defined by 25 the beading 8. Between the border of the ornamentation 7 and the curved edge 9 (between the heads forming the angles) are a series of floral ornamentations 10 11. All of the surface ornamentations are in relief. 30

I claim—

The design for a base for match-box holders, or similar articles, substantially as herein shown and described.

Signed at the city of New York, (Brooklyn,) 35 county of Kings, and State of New York, this 12th day of April, 1900.

FRANK J. GRESSLY.
